By Charles P. Hannigan,
Attorney.

UNITED STATES PATENT OFFICE.

GEORGE E. STILLMAN, OF PROVIDENCE, RHODE ISLAND.

BALL-COCK.

SPECIFICATION forming part of Letters Patent No. 767,848, dated August 16, 1904.

Application filed February 5, 1904. Serial No. 192,209. (No model.)

To all whom it may concern:

Be it known that I, GEORGE E. STILLMAN, a citizen of the United States, residing at the city of Providence, in the county of Providence and State of Rhode Island, have invented 5 certain new and useful Improvements in Ball-Cocks, of which the following is a specification.

My invention has for its object to simplify 10 the structure of parts in connection with the valve and means carried by the float-rod to actuate in opening and closing said valve and so arranged that the ball-cock may be applied to a tank to give either a top supply or 15 a bottom supply, as may be desired.

The invention consists of the novel construction and combination of parts, as herein-after described, and specifically set forth in the claims.

20 In the accompanying sheet of drawings, Figure 1 represents a central longitudinal section of a ball-cock, showing its valve closed, as when the supply is shut off and the float at its upper position in the tank. Fig. 2 is 25 a similar view of the ball-cock, showing the normal position of parts, as when the float is at its lower extremity in the bottom of the tank and has actuated to open the valve. Fig. 3 shows my improved ball-cock as applied to 30 the side of a tank, as for a top supply. Fig. 4 is a similar view showing the ball-cock applied to the bottom of a tank, as for a bottom supply. Fig. 5 is a side elevation of the valve. Fig. 6 is an end view of the valve 35 and showing a packing-disk secured in place thereon. Fig. 7 is an end elevation of a strainer or screw-plug. Fig. 8 is a central longitudinal section of the same. Fig. 9 is an enlarged cross-sectional view of the valve- 40 stem and its support, taken on line xx of Fig. 1. Fig. 10 is a perspective view of an attachable clip for the ball-cock casing, together with a Y-shaped extension pivoted on said clip and adapted to receive the end of the 45 float-rod.

Like letters of reference indicate like parts.

A is the ball-cock casing of a tubular form and having an integral transverse partition b , situated near the central portion of the cas-

ing, so as to form two chambers in the same, 50 as c and c' . The partition b is provided with a circular opening or port c^2 , communicating with the chambers c and c' and formed concentric with the bore of the casing A, and said port c^2 is surrounded by an annular flange 55 that extends in the chamber c of the casing and which flange forms a valve-seat, as at b' .

D is the valve as a whole, having an enlarged circular head d and an integral stem projecting centrally from one end thereof, as 60 at d' , and the opposite or front end of the head d is provided with a recess to receive a flexible disk d^2 . (See Fig. 6.) The disk d^2 is secured in place within the recess of the valve D by a screw d^3 , and said disk is arranged to find its resting-place upon the valve-seat b' of the casing. 65

E is a circular strainer or screw-plug having an enlarged head e and whose peripheral surface is screw-threaded to fit tightly within 70 the threaded end portion of the chamber c of the casing. This strainer or screw-plug E has a central integral tube e' projecting in the chamber c and arranged to act as a support for the stem d' of the valve D. Said strainer or 75 screw-plug is provided with a series of perforations e^2 , formed in its head e thereof and surrounding its tube or valve-support, as shown at Fig. 7.

F is a screw-plug having an enlarged hexagonal head f , integral at one end, and said screw-plug is provided with an exterior screw-threaded portion extending inwardly of the head f and arranged to fit snug in a screw-threaded opening formed in the opposite end 80 of the casing A, as at f' . This screw-plug F is drilled centrally and longitudinally throughout its length to form a bearing-support for a 85 slideable rod G. This rod has an enlarged integral collar g formed near its middle portion and arranged as a stop to prevent withdrawal of said rod when said screw-plug F is mounted in the ball-cock casing. The rod G when mounted as described has its longitudinal center in alignment with the longitudinal center of the valve D. 90

Between the head f of the screw-plug F and the end of the casing A is interposed a thin

metallic clip H, made in one piece, having a disk h, which is provided with a centrally-circular opening h' to fit loosely upon the threaded portion of said screw-plug F. This clip has 5 a fork or bifurcated portion, as h'', to project outwardly from the casing A.

The screw-plug F not only serves as a bearing-support for the rod G, but also acts as a clamp to impinge against and hold the clip 10 H firmly in position upon the casing in the manner shown in Figs. 1 and 2.

I is a Y-shaped extension or member which has one end pivotally mounted on a pin i, secured in the fork or bifurcated portion of 15 the clip H, and the opposite portion of said member or extension exposing two outwardly-projecting hubs or arms i' i'', provided each with a screw-threaded aperture to receive the threaded end of the float-rod j. This Y-shaped member or extension I has a spur i'', formed at a point intermediate of its pivotal center and its arms, and said spur is adapted to contact with the outer end of the slideable rod G in forcing the valve D from its seat.

25 The ball-cock is mounted in position upon a water-tank, as follows: The tank (designated by letter T) is provided with a circular opening formed in its side and situated near the top of said tank, as at t in Fig. 3. The 30 portion of the casing A which contains the strainer or screw-plug E is passed through said opening t until prevented by a packing-ring t', which surrounds the casing and abutting an integral annular flange t'' thereof. 35 The outer portion of the casing has an exterior screw-thread, as t'', to receive a flangenut u, which impinges against the outer surface of the tank and holds the ball-cock firmly in position upon the same.

40 v is the inlet or supply pipe, having an outwardly-projecting annular flange v' at one end to abut against a packing-ring w, which adjoins the face of the head e of the strainer or screw-plug E.

45 x is a coupling-nut mounted on the screw-threaded portion t' of the casing A, and said coupling-nut has an inwardly-projecting annular flange to abut against the annular flange v' of the supply-pipe v, so that by screwing 50 up the said nut x the supply-pipe is firmly secured to the ball-cock.

The strainer or screw-plug E has a recess formed in the outer face of its head e, as at e', so that should the packing-ring w be compressed too far inwardly by the coupling-nut x a sufficient clearance or passage is maintained for the flow of water-pressure from the supply-pipe through the perforations e' of said strainer or screw-plug.

60 The casing A is provided with a discharge-pipe y, which has one end made fast within an annular flange-hub integral with the side of the casing, and said discharge-pipe y communicates with the chamber c' thereof and

has its opposite ends terminating at a point 65 near to the bottom of the tank T, as shown in Fig. 3.

When the ball-cock is mounted horizontally on the tank, as described, the clip member H is designed to be held or fixed in one position 70 by the bolt f and at the same time with its fork or bifurcated portion uppermost from the casing, as seen in Figs. 1, 2, and 3. In this position of the ball-cock the end of the float-rod j would be attached or connected to 75 the uppermost arm of the Y-shaped member or extension I, as shown.

The operation of my improved ball-cock is as follows: Assuming that the tank T is full of water reaching to a level, as at a point l in 80 Fig. 3, when the ordinary pull-chain is operated upon to open the waste-valve (not shown) the amount of water contained in said tank will pass down and out through the waste-pipe z, and as the water lowers in the tank 85 the float-ball j'' descends and by its rod connection with the Y-piece member I causes the spur i'' of the latter to contact against the end of the slideable rod G and which movement gradually forces the valve-disk d'' from its 90 seat to the position shown in Fig. 2. By this time the float-ball j'' will have reached its lower extremity in the tank to the dotted position indicated in Fig. 3, when the water-supply from the inlet v will pass from the chamber c, thence through the port c', through the chamber c', and, finally, through the pipe y to be discharged in the tank, and which discharge carries the float-ball again up to its 95 normal position, when the valve will be closed 100 by the pressure from the inlet. The discharge-pipe y is provided with a perforation, as y', which forms an air-hole to prevent siphonage when the water-supply is shut off. To prevent rotation of the valve D and make the 105 same noiseless during the time said valve is open and the supply is in force, I have one side of the valve-stem d' made flat to adjoin a 110 flat side formed on the support e' of the strainer or screw-plug in the manner shown in Fig. 9.

This ball-cock may be applied to operate in a vertical position upon the bottom of the tank. In this case the end of the float-rod j would be attached in the screw-threaded aperture of the lowermost arm of the Y-piece I and the discharge-pipe y withdrawn from the casing, so that the ball-cock would operate as in the position shown in Fig. 4. By this simple construction and arrangement of parts I 115 form a ball-cock which has the advantage of being readily applied to operate either in a horizontal or vertical position for a top supply or a bottom supply and at the same time 120 has the advantage in that the strainer and valve can be quickly removed from their position in the casing by simply unscrewing the 125 coupling-nut to cleanse the strainer from sedi-

ment or to replace a new valve-disk when necessary.

What I claim, and desire to secure by Letters Patent, is—

- 5 1. In a ball-cock having a tubular casing which is divided by a central transverse partition provided with a port, and said casing having a supply-pipe properly connected at one end and a discharge-pipe to enter the side 10 thereof, the combination therewith, of a screw-plug fixedly secured in the supply end of said casing and provided with perforations forming a water-passage and arranged to prevent sediment from passing therethrough; a 15 valve slidably mounted in said screw-plug; a flexible disk secured on said valve and adapted to close the port in said casing; a slide-rod properly mounted in said casing, and of a length to project from the same; a clip member 20 fixedly secured upon said casing; a Y-shaped member pivoted on said clip and having a spur to contact with the projecting end of said slide-rod to force the valve from its seat, and said Y-shaped member having its 25 extending arms provided each with a screw-threaded aperture for attaching therein the threaded end of a float-rod, in accordance to the relative operating position of the ball-cock, substantially as set forth.
- 30 2. In a ball-cock having a tubular casing which is divided by a central transverse partition, so as to expose a supply-chamber and discharge-chamber at each side thereof, and said casing provided with a port in its partition and communicating with the chambers thereof, the combination therewith, of a strainer member having an enlarged head fixed in the supply end of said casing and having an inwardly-projecting tube, and said 35 strainer member provided with a recess and a series of perforations formed in its head; a supply-pipe having an outwardly-extending annular flange at one end thereof; a packing-ring interposed between the head of said 40 strainer member and the flange of said supply-pipe; a coupling-nut mounted on said casing and having an inwardly-extending annular flange to close over the flange of said sup-
- ply-pipe; a valve slidably mounted in the tube of said strainer member; means to prevent rotation of said valve when mounted on said strainer member; a flexible disk secured to said valve and arranged to close the port in said casing; a slide-rod properly mounted in said casing and extending within the discharge-chamber thereof; means to prevent withdrawal of said slide-rod when mounted on said casing; a clip member fixed to said casing; a Y-shaped extension pivotally connected to said clip member and having a spur to engage upon the outer end of said slide-rod to force said valve open, and said extension having arms to receive and hold the end of the float-rod, substantially as set forth. 50
3. In a ball-cock having a tubular casing, 65 which is divided by a central transverse partition having a port-opening, communicating with the supply and discharge chambers of the casing, the combination, of a strainer fixed in the supply end of said casing; a slide-rod 70 mounted in said strainer; a flexible disk fixed to said valve and arranged to close the port in said casing; a screw-plug mounted in said casing and provided with a bore; a slide-rod loosely mounted in the bore of said screw-plug, and having an integral collar arranged to prevent the withdrawal of said slide-rod from the same; a clip secured by said screw-plug upon said casing and having an integral bifurcated portion; an extension pivotally 75 mounted on the bifurcated portion of said clip and having a spur to contact with said slide-rod to open said valve, and said extension having two outwardly-projecting arms which are each provided with an aperture for 80 attaching therein the end of the float-rod, in accordance to the different normal position of the ball-cock, substantially as shown and described. 85
- In testimony whereof I affix my signature in 90 the presence of two witnesses.
